UNITED STATES PATENT OFFICE

1,993,194

PNEUMATIC DISPATCH SYSTEM

Fred R. Taisey, Lowell, Mass., assignor to The Lamson Company, Syracuse, N. Y., a corporation of Massachusetts

Application January 28, 1932, Serial No. 589,376

12 Claims. (Cl. 243—34)

This invention relates to an improvement in a pneumatic dispatch system and more particularly in the carrier for such system.

The carriers are of the usual well known construction including a barrel comprising an outer and an inner shell telescopically arranged and relatively rotatable, each shell having an access opening in the side thereof, such opening being brought into or out of register by the rotation 5 of the shells, and at each end of the barrel a head and a flexible skirt the head and skirt at one end being attached to the outer shell and at the other end being attached to the inner shell.

Since the heads and skirts become worn as the 15 result of use one object of this invention is to provide means by which the heads and/or skirts can be quickly and easily detached from the shells and replaced.

Another object of this invention is to provide 20 means by which the shells of the barrel are yieldably held in a predetermined position relative to each other preferably in such position that the access openings are out of register and the contents of the carrier can not escape until it is desired to remove them.

A further object of this invention is to provide 25 means by which the carriers can be readily sorted without examining the contents thereof, as for example, into various groups according to the destination of the carriers or according to the contents thereof. One way of so doing, previously practiced has been to color the heads of the carriers but it has been found that this treatment 30 of the heads, particularly when, as is the usual custom, the heads are of felt, affects the wearing qualities thereof and necessitates more frequent replacements. Accordingly it is proposed to attain this result by making the barrel 35 shells of fibre instead of metal, and to color the barrel shells to designate the contents of the carrier while the heads, contrary to the present practice, are uncolored.

Other objects of this invention will appear in 40 the following description and in the drawing which forms a part thereof and in which:

Fig. 1 is a side elevation of a carrier embodying 45 one form of this invention;

Fig. 2 is an end elevation of such carrier;

Fig. 3 is a sectional view taken along the line 50 3—3 in Fig. 1;

Fig. 4 is an exploded view of the right end of the carrier shown in Fig. 1, the various elements 55 being shown separated and partly in section in

order to demonstrate their structure and relation;

Fig. 5 illustrates in elevation the lock plate at the left end of the carrier shown in Fig. 1;

Fig. 6 is a sectional side view of one end of a carrier embodying this invention having a different form of latching means from that shown in Fig. 1;

Fig. 7 is a cross section of the carrier shown in Fig. 6 taken on the line 7—7 therein;

Fig. 8 illustrates in elevation carriers, the barrels of which are differently colored in accordance with one feature of this invention;

Fig. 9 is a fragmentary side elevation of another form of lock plate;

Fig. 10 is a fragmentary section of another form of cup member; and

Fig. 11 is a fragmentary section of another form of washer.

The carrier disclosed in the drawing comprises 20 a barrel 10 at each end of which is mounted a skirt 11 and a head 12. The barrel 10 comprises an outer shell 15 and an inner shell 16, each having in its side wall an access opening designated as 17 and 18 respectively. The shells are telescoped one over the other and are relatively rotatable so that when the openings 17 and 18 are 25 in register access may be had to the interior of the barrel. The skirt and head at one end of the carrier are attached to the outer shell 15, while the skirt and head at the other end are attached to the inner shell 16 so that the shells may be rotated by manipulating the heads.

The skirts 11 are disks of rubber or other flexible material and are located between flanges at 35 the ends of the shells and the heads 12. The heads each comprise a ring 20 of felt or the like, a cup 21, surrounded by the ring, the edge of the cup entering a groove in the ring, and a washer 22 having outwardly projecting pins 23 which 40 enter the ring 20 and hold it in the proper position about the cup. Prongs 24 projecting from the edge of the cup 21 enter the body of the head and prevent any relative rotation.

The skirt 11 and head 12 are attached to the shells by means of a lock plate 25, from which project lock pins 26. The lock plate 25 at the right end of the carrier, shown in Figs. 1 and 4, rests upon a spring cup 27 and the pins 26 which 50 pass through suitably located openings in the plate and cup are headed over to unite the plate and cup. The spring cup 27 enters the end of the inner shell 16, and turns freely therein, while the lock plate 25 is provided with tongues 28 55

which enter notches 29 in the flange of the outer shell 15, so that the plate and cup move in unison therewith. The lock pins 26 pass through openings 30 in the skirt 11 and openings 31 in the base of the cup 21 and have at their outer end notches 32 with which a lock spring plate 33 engages to secure the elements, as shown in Figs. 1 and 2. The ends 34 of the spring plate 33 are arcuate (see Fig. 2) and extend substantially to the walls of the cup 21. Adjacent one side of each end 34 is formed a recess 35 through which the lock pins 26 pass freely. Between each recess 35 and the other end 34 of the spring plate are provided curved projecting portions 36 which, when the plate is rotated, enter the notches 32 of the pins 26. The portions 36 as shown in Fig. 4 are bent upwardly and downwardly out of the plane of the body of the plate and bear against the base of the cup and against the outer walls of the notches 32 thus yieldably holding the head 12 against the end of the shell. A central slot 37 in the spring plate is adapted to receive the end of the screw-driver or other instrumentality by which the spring plate is rotated. Bosses or depressions 38 in the ends 34 engaging corresponding depressions or bosses (not shown) in the base of the cup or other suitable means are provided to hold the spring plate in the locking position. In addition there may be employed at each end a cotter pin 39 which enters one of the recesses 35 and positively prevents any shifting of the plate 33.

The spring cup 27 includes diametrically located bosses 40 which engage a block 41 secured to the inner wall of the shell 16 and thereby limit the relative rotation of the shells. In order to secure the shells against involuntary relative rotation when the access openings are closed a spring latch 42 is mounted upon the cup. The latch is secured at one end to the wall of the cup and terminates at the other end in a projection 43 which, when the openings are closed, enters a notch 44 in the inner shell.

The skirt 11 and head 12 at the left end of the carrier shown in Fig. 1 is attached to the inner shell 16 by locking means similar in all respects to those previously described in detail and hence the same reference characters have been employed without further description. It will be noted that the end of the inner shell is flanged and has notches 45 therein which receive the tongues 28 of the lock plate 25.

The cups 21 provide central depressions at the ends of the carriers. Hence when the carriers are used in a system which includes a separator that relies upon the presence of or absence of such depression, such as that shown in my prior Patent No. 1,218,910, it is necessary that the depressions in the cups be closed as for example by securing plugs therein. One such plug designated as 46 is shown in dotted lines in Fig. 6. For the purpose of securing the plugs holes 47 may be formed in the walls of the cups so that the plugs may be secured by cement which enters the head 12 through the holes 47.

In Figs. 6 and 7 is illustrated one end of a carrier embodying this invention but provided with means for latching the carrier closed which differ from those previously described. The head and skirt and the means for locking them in place are the same as those shown at the left end of Fig. 1. Reference numerals will accordingly be employed without any further description, it being understood that such numerals are primes of the numerals used for the correspond-

ing elements. A pin 50 projecting inwardly from the outer shell 15' engages recesses 51 in the walls of the side opening 18' in the inner shell 16' and thus limits the opening and closing movements of the shells. A strip 55 of spring metal is secured at one end to the inner wall of the shell 16' and carries at its other end a projection 56 which extends through an aperture 57 in the inner shell into contact with the outer shell 15'. In the outer shell 15' is formed an aperture 58 which receives the projection 56 when the carrier is closed and latches the shells in such position.

In using carriers it has been found that means should be provided by which the carriers may be sorted into groups according to their destinations or according to the character of their contents without the necessity of opening the carriers. Thus if the carriers are to be used for transporting three different kinds or classes of contents it is a great assistance to be able to recognize the carriers containing each kind or class. Heretofore this has been done by coloring the carrier heads but this treatment has been found to affect adversely the life and wearing qualities of the heads. Moreover in the case of replacements it is necessary to have a supply of heads of the various colors so that the carriers after such replacement may be used as before. The barrel shells of the carriers embodying this feature of the invention are of fibre which not only reduces the weight of the carriers but also can readily be colored to indicate the various classes of carriers. Thus as indicated on Fig. 8, the carriers A, B and C differ in the colors of the barrels the barrel of carrier A being red, that of carrier B being blue and that of carrier C being green. The fibre shells are colored by painting, dipping or otherwise treating them and the colors, due to the fibrous composition of the shells, enter the pores of the shells and are incorporated therein so that they are not removed or obliterated by handling. It will be understood that these colors were selected arbitrarily and that this invention is not in any way limited to the colors or the arrangement thereof here shown.

Figs. 9, 10 and 11 illustrate other forms of certain elements which may be employed in place of those previously described. The lock plate 60 shown in Fig. 9 differs from that shown and described as 25 in that the pins 61 have annular grooves 62 therein instead of the notches 32. The cup 65 shown in Fig. 10 which may be used in place of that designated at 21 includes an annular flange 66 around each base opening 67. The prongs 68 projecting from the edge of the cup, the base openings 67 and the openings 69 in the walls correspond in structure and function to the prongs 24, the base openings 31 and the openings 47 described above. In place of the washer 22 having outwardly projecting pins 23 the washer 70 may be used. The washer 70 is provided with an annular depression 71 and at the edge includes integral prongs 72 which function in the same way as the pins 23 to engage the felt head.

While several forms of carriers embodying this invention have been shown and described I am not limited thereto since other embodiments may be made without departing from the spirit and scope of the invention as set forth in the following claims.

I claim:

1. In a carrier for a pneumatic dispatch system comprising a barrel and heads at the ends there-

- of, said barrel including an outer and an inner shell telescopically arranged, and one head being detachably secured to the outer shell and the other head being detachably secured to the inner shell, means for attaching each head to the corresponding shell comprising a lock plate in engagement with the shell, pins projecting from said plate into said head and a locking plate in said head movable into and out of a position 5 in which it contacts with said pins whereby the head is secured to or released from the shell.
2. In a carrier for a pneumatic dispatch system comprising a barrel and heads at the ends thereof, said barrel including an outer and an inner shell telescopically arranged, and one head being detachably secured to the outer shell and the other head being detachably secured to the inner shell, means for attaching each head to the corresponding shell comprising a lock plate in 10 engagement with the shell, pins projecting from said plate into said head the outer ends of which pins are notched and a locking plate in said head adapted to enter the notches and secure the head to the shell.
- 20 3. In a carrier for a pneumatic dispatch system comprising a barrel and heads at the ends thereof, said barrel including an outer and an inner shell telescopically arranged, and one head being detachably secured to the outer shell and the other head being detachably secured to the inner shell, said heads each including a cup and a ring surrounding the cup, means for attaching each head to the corresponding shell, comprising a lock plate in engagement with the shell, pins projecting from said plate into the cup of the head through holes therein and a locking plate in said cup coacting with said pins to secure the head to the shell. 25
4. In a carrier for a pneumatic dispatch system comprising a barrel and heads at the ends thereof, said barrel including an outer and an inner shell telescopically arranged, and one head being detachably secured to the outer shell and the other head being detachably secured to the inner shell said heads each including a cup and a ring surrounding the cup, means for attaching each head to the corresponding shell, comprising a lock plate in engagement with the shell, pins projecting from said plate into the cup of the head through holes therein, the ends of the pins within the cup being notched and a locking plate in the cup for engaging the notches in the pins and securing the head to the shell. 30
5. In a carrier for a pneumatic dispatch system comprising a barrel and heads at the ends thereof, said barrel including an outer and an inner shell telescopically arranged, and one head being detachably secured to the outer shell and the other head being detachably secured to the inner shell, said heads each including a cup and a ring surrounding the cup, means for attaching each head to the corresponding shell, comprising a lock plate in engagement with the shell, pins projecting from said plate into the cup of the head through holes in the base thereof, and a locking plate in said cup and rotatable into engagement with said pins to secure the head to the shell. 35
6. In a carrier for a pneumatic dispatch system comprising a barrel and heads at the ends thereof, said barrel including an outer and an inner shell telescopically arranged, and one head being detachably secured to the outer shell and the other head being detachably secured to the inner shell, said heads each including a cup and a ring surrounding the cup, means for attaching each head to the corresponding shell, comprising a lock plate in engagement with the shell, pins projecting from said plate into the cup of the head through holes in the base thereof, and a locking plate in said cup and rotatable into engagement with said pins to secure the head to the shell. 40
7. In a carrier for a pneumatic dispatch system comprising a barrel and heads at the ends thereof, said barrel including an outer and an inner shell telescopically arranged, one head being secured to the outer shell and the other head being secured to the inner shell, each shell terminating in a notched flange adjacent the head secured to it, means for attaching each head to the corresponding shell comprising a lock plate in contact with the shell flange and in engagement with the notch therein to prevent relative rotation, pins projecting from said plate into said head and a locking plate movable into and out of a position in which it contacts with said pins whereby the head is secured to or released from the shell. 45
8. In a carrier for a pneumatic dispatch system comprising a barrel and heads at the ends thereof, said barrel including an outer and an inner shell telescopically arranged, one head being secured to the outer shell and the other head being secured to the inner shell, each shell terminating in a notched flange adjacent the head secured to it, and each head comprising a cup having holes in the base thereof and a ring surrounding said cup, means for attaching each head to the corresponding shell comprising a lock plate in contact with the shell flange and in engagement with the notch therein to prevent relative rotation, pins projecting from said plate into the cup of the head through the holes in the base, the ends of said pins within the cup being notched and a locking plate in the cup for engaging the notches in the pins and securing the head to the shell. 50
9. In a carrier for a pneumatic dispatch system comprising a barrel and heads at the ends thereof, said barrel including an outer and an inner shell telescopically arranged, one head being secured to the outer shell and the other head being secured to the inner shell, each shell terminating in a notched flange adjacent the head secured to it and each head comprising a cup having holes in the base thereof and a ring surrounding said cup, means for attaching each head to the corresponding shell comprising a lock plate in contact with the shell flange and in engagement with the notch therein to prevent relative rotation, pins projecting from said plate into the cup of the head through the holes in the base, the ends of said pins within the cup being notched and a locking spring plate in the cup for engaging the notches in the pins and bearing yieldably against the base of the cup to secure the head to the shell. 55
10. In a carrier for a pneumatic dispatch system comprising a barrel and heads at the end thereof, said barrel including an outer and an inner shell telescopically arranged, a plate carried by the outer shell by which one head is secured thereto and a plate carried by the inner shell by which the other head is secured thereto, each shell having an access opening in the side which openings are brought into and out of register by the relative rotation of the shells, means for limiting such rotation of the shells and means 60
- 70
- 75

supported by the plate carried by one shell for yieldably engaging the other shell at one limit of their travel to hold the shells in such position.

11. In a carrier for a pneumatic dispatch system comprising a barrel and heads at the ends thereof, said barrel including an outer and an inner shell telescopically arranged, a plate carried by the outer shell by which one head is secured thereto, the other head being secured to the inner shell, each shell having an access opening in the side which openings are brought into and out of register by the relative rotation of the shells, a cup attached to said plate, means on the cup and plate for limiting such rotation of the shells, and means on the cup for yieldably engaging the inner shell at their limit of travel in which the

openings are out of register to hold the shells in such position.

12. In a carrier for a pneumatic dispatch system comprising a barrel and heads at the ends thereof, said barrel including an outer and an inner shell telescopically arranged, a plate carried by the outer shell by which one head is secured thereto, the other head being secured to the inner shell, each shell having an access opening in the side, which openings are brought into and out of register by the relative rotation of the shells, a cup attached to said plate, means on the cup and plate for limiting such rotation of the shells and means on the cup for engaging the inner shell at one limit of travel for holding the shells yieldably in such position.

FRED R. TAISEY.
